JOHN D. HARRIS,

By A.C. Biemiller Attorney

UNITED STATES PATENT OFFICE

JOHN D. HARRIS, OF LARCHMONT, NEW YORK

RUG

Application filed February 16, 1932. Serial No. 593,285.

This invention relates to the manufacture of rugs, more particularly to rugs having a felt base.

There has been well known on the market 5 the so-called "India" or "Numdah" rug, which as its name implies is manufactured in India and surrounding countries. It comprises a thin felt base, having designs hand woven with woolen threads thereon. Rugs 10 of this character are comparatively weak, due to the felt base and the thinness thereof, so that in use they quickly deteriorate.

Furthermore, the sizes of the rugs are irregular, it being almost impossible to obtain 15 rugs of standard size such as are desirable in the American trade. The colors of the bases cannot be controlled as the workers in India choose their own colors which may not be saleable in this country. Often the designs 20 on the rugs do not meet with favor here and the importer may find himself with unsaleable rugs on his hands. Because of the thinness of the felt base, the India rug does not have the soft cushion like effect which is 25 highly desirable to the trade.

In view of the disadvantages of this type of rug, some of which have been enumerated above, it becomes highly desirable to have a rug of this character, all the factors of which 30 may be under complete control. It is, therefore, the object of this invention to provide a felt base rug which is strong, which is readily made in regular sizes, wherein the colors and the designs may be easily controlled and which has the soft cushion like 35 effect when walking on it.

It is also among the objects of this invention to provide a process of making the same 40 which will render this type of rug cheap and highly durable.

In practicing my invention I provide a thick felt base, which is in all cases greater than $\frac{1}{8}$ of an inch, and may be as thick as $\frac{1}{4}$ of an inch or greater. The base is made of 45 at least two layers of felt, having therebetween a layer of coarse mesh woven fabric of a material which is stronger than the base. Usually this fabric is of cotton that is spun fibers. It so reinforces the felt base that 50 it may now be easily and readily worked.

in a machine operating at high speed without distorting or tearing, or otherwise injuring the felt base.

I place this base in a shuttle embroidering machine, and embroider thereon a suitable design. Ordinarily the base is of such size that a plurality of rugs are embroidered at the same time, the finished product being taken from the machine and cut apart into a number of rugs.

In order to make possible the placing of the felt base in the machine and to allow it to be embroidered without difficulties, I provide a basted woven fabric or tape along the edges of the felt base. Preferably it extends around the entire circumference of the base, but it may be placed only at intervals or portions thereof. This fabric serves the purpose of holding the felt base firmly in position in the embroidering machine.

I have found that it is impossible to utilize in the embroidering the ordinary wool yarn which had heretofore been used in the hand made rugs. I found that in attempting to work the embroidery into the felt that because of the thickness of the felt and particularly because of the presence of the fabric therein, the wool yarn was cut and injured so that it became impossible to embroider a design on the base. After a considerable amount of experimentation it was determined that it was essential to have a thread which was stronger than the base. I found that a thread having a core of cotton with wool surrounding the same to give it the appearance of a wool yarn was suitable for my purpose. I also found that an all cotton thread, that is, a thread of spun fibers, which may be termed a coarse size of combed peeler 80 yarn was also suitable in this process.

In the accompanying drawing constituting a part hereof, and in which like reference characters indicate like parts:

Figure 1 is a plan view of a plurality of rugs integrally united and in the condition in which the article is taken from the machine after completion of the design.

Figure 2 is a fragmentary view of a corner of a rug showing the character and location of the reinforcing fabric therein, and

Figure 3 is a fragmentary sectional view taken through line 3—3 of Figure 1.

The article comprises the base 1 of felt, consisting of two layers 2 and 3 of felt, having therebetween a cotton or like fabric 4, which is ordinarily of coarse mesh, although it may be finely woven. I prefer a coarse mesh because it allows the layers of felt to be more firmly united and it offers less resistance of the passage of needles of the embroidering machine. It, therefore, enables the use of thicker bases than would otherwise be the case.

Along the edges of the base 1 are basted a series of tapes or strips of woven fabric 5, 6, 7 and 8 by basting stitches 9. The material is then placed in a shuttle embroidering machine, the fabric strips being secured to pins in the machine which hold the base 1 rigidly in position. The machine is then caused to embroider designs 10 and 11 on the base 1, each of these designs being on a separate rug. The article is then removed from the machine, the tape 5, 6, 7 and 8 removed and the rugs cut apart at point 14. They are now completed and ready for the market.

It will be noted that my process results in the manufacture quickly and by machine methods of a plurality of rugs of uniform predetermined and controlled designs and colors. Whereas rugs of this character made by hand have heretofore been mostly in dark colors it is now possible for the first time to have this type of rug made with bases of light or pastel shades. If a demand arises for certain colors of base, certain designs or certain coloring of designs, the machines may be quickly changed to give the popular character of rug desired at the time. This was impossible with the old imported rug because of the impossibility of quickly changing, in view of the fact that it took months to manufacture such rugs, and it took weeks for shipment thereof to this country.

Although I have described my invention setting forth a single embodiment thereof, it will be apparent to those skilled in the art that many variations in the construction and in the process of manufacture of my rug may be made within the scope of the invention. For example, although I have shown the manufacture of two rugs integrally united, in ordinary practice I make considerably more than two rugs and the rugs may be varied in size and in design at will. It is not absolutely essential to have the tape continuous and on all four sides of the base as it may be possible to utilize discontinuous tape or even tabs at considerable intervals to hold the base in the machine. The base may be of more than two layers of felt and there may be more than one layer of fabric therein to give additional strength or additional thickness. These and other changes may be made in my invention, within the spirit thereof,

the character of my invention being set forth in the claims appended hereto.

What I claim is:

1. An article of manufacture comprising a rug having a base of at least one layer of felt, a fabric of spun fibers on one side of said layer, a design embroidered on said base, the threads of said design being of spun fibers and passing through said felt and fabric, the design appearing on the surface of the felt opposite to said fabric.

2. An article of manufacture comprising a rug having a base of a plurality of layers of felt, a fabric of spun fibers interposed between said layers, and a design embroidered on said base, the threads of said design being of spun fibers and passing through said felt and fabric.

3. An article of manufacture comprising a rug having a base of a plurality of layers of felt, a fabric of spun fibers interposed between said layers, and a design embroidered on said base, the threads of said design being of spun fibers resembling wool yarn and passing through said felt and fabric.

4. An article of manufacture comprising a rug having a base of a plurality of layers of felt, a fabric of spun fibers interposed between said layers, and a design embroidered on said base, the threads of said design being of spun fibers with wool surrounding said spun fibers and passing through said felt and fabric.

5. An article of manufacture comprising a rug having a base of a plurality of layers of felt, a fabric of spun fibers interposed between said layers, and a design embroidered on said base, the threads of said design being of coarse size combed peeler yarn and passing through said felt and fabric.

In testimony whereof, I have hereunto subscribed my name this 11th day of February, 1932.

JOHN D. HARRIS.
